UNITED STATES PATENT OFFICE

153,738

DESIGN FOR A TABLE OR SIMILAR ARTICLE

Donald A. Wallace, New York, N. Y.

Application April 23, 1947, Serial No. 138,543

Term of patent 3½ years

(Cl. D33—14)

To all whom it may concern:

Be it known that I, Donald A. Wallace, a citizen of the United States, residing at New York, in the county of Queens and State of New York, have invented a new, original, and ornamental Design for a Table or Similar Article, of which the following is a specification, reference being had to the accompanying drawings, forming a part thereof.

I claim:

The ornamental design for a table or similar article, as shown.

DONALD A. WALLACE.
